STORAGE DRUM OR SIMILAR ARTICLE

Charles A. Speas, Towson, Md., assignor to Hedwin Corporation, New York, N.Y., a corporation of Maryland

Filed May 31, 1963, Ser. No. 75,154

Term of patent 14 years

(Cl. D58—3)

FIGURE 1 is a side elevational view of a storage drum or similar article showing my new design;

FIGURE 2 is a top plan view thereof;

FIGURE 3 is a bottom plan view;

FIGURE 4 is an enlarged sectional view taken on line 4—4 of FIGURE 2;

FIGURE 5 is an enlarged sectional view taken on line 5—5 of FIGURE 2;

FIGURE 6 is an enlarged sectional view taken on line 6—6 of FIGURE 2; and

FIGURE 7 is an enlarged sectional view taken on line 7—7 of FIGURE 3.

The essential features of my design reside in the portions shown in full lines in the drawing and consist of a storage drum having top and bottom closures respectively bounded by upstanding annular rims defining the outer extremities of a series of radiating corrugations of rounded, cross-sectional contour and lying within the

vertical limits of the bounding rims, the top closure having a plurality of radially extending ears which project upwardly beyond said rim, the bottom closure having a ring-like rib at its center, and the top closure having a pair of crossed ribs at its center, all as shown.

I claim:

The ornamental design for a storage drum or similar article, as shown and described.
